UNITED STATES PATENT OFFICE.

WILLIAM F. LITTLE, OF ST. LOUIS, MISSOURI.

DESIGN FOR AN IDENTIFICATION AND REGISTRATION PLATE FOR AUTOMOBILES.

Application filed October 23, 1922. Serial No. 4,057. Term of patent 14 years.

To all whom it may concern:

Be it known that I, WILLIAM F. LITTLE, a citizen of the United States of America, residing at St. Louis, in the State of Missouri, have invented a new, original, and ornamental Design for Identification and Registration Plate for Automobiles, of which the following is a specification, reference being had to the accompanying drawing, forming part thereof.

The figure shows the face of the plate.

I claim:

The ornamental design for an identification and registration plate for automobiles, as shown.

WILLIAM F. LITTLE.
